(57) **CLAIM**

I claim the ornamental design for a snow-melting carpet, as shown and described.

DESCRIPTION

FIG. 1 is a perspective view of a snow-melting carpet showing my new design;

FIG. 2 is a top plan view thereof;

FIG. 3 is a side elevational view thereof;

FIG. 4 is a side elevational view of the opposing side thereof;

FIG. 5 is a bottom plan view thereof;

FIG. 6 is an end elevational view thereof;

FIG. 7 is an elevational view of the opposing end thereof; and,

FIG. 8 is a reduced scale, partial perspective view showing the snow-melting carpet in use, it being understood that the power cord is not fully shown in this view. The broken lines depict environmental structure, as well as the point at which the power cord is broken away, for illustrative purposes only and form no part of the claimed design.
